[57] CLAIM

The ornamental design for a kiosk for automatic banking or the like, substantially as shown and described.

DESCRIPTION

FIG. 1 is a side elevational view of the kiosk for automatic banking or the like;

FIG. 2 is a front elevational view thereof;

FIG. 3 is a top plan view thereof;

FIG. 4 is a bottom plan view thereof;

FIG. 5 is a side elevational view of the side opposite that shown in FIG. 1;

FIG. 6 is a rear elevational view thereof; and

FIG. 7 is a sectional view of the novel design as taken along lines 7—7 of FIG. 6.
